UNITED STATES PATENT OFFICE.

EDWARD J. DUNIGAN, OF MUSKOGEE, OKLAHOMA.

DRILL JAR.

Application filed June 25, 1925. Serial No. 39,573.

To all whom it may concern:

Be it known that I, EDWARD J. DUNIGAN, a citizen of the United States, residing at Muskogee, in the county of Muskogee and State of Oklahoma, have invented new and useful Improvements in Drill Jars, of which the following is a specification.

This invention relates to drill jars and embodies an improvement on the drill jar disclosed in my pending application Serial No. 617,331, filed Feb. 6, 1923.

The primary object of the present invention is to provide an extension of the knocking head the full length of the tongue in each member or element of the jar, and thus reinforce each tongue and prevent the same from fracturing or breaking off, which is liable to happen, and render the jar unfit for further use.

A further object of the present invention is to extend the knocking head the full length of the tongue of each jar member to protect the tongue and also cause the extension to assume a part of the jar and thus render the tongue more durable and generally preserve the operativeness and advantages of each tongue at its extreme end.

A still further object of the present invention is to generally embody the advantages of my prior structure as disclosed by the above noted application and materially add to the advantages of said structure by protecting the tongue of each jar member or unit and more evenly distribute the jar stress over the entire jar structure.

With these and other objects and advantages in view as will hereinafter appear in detail, the invention consists in the construction and arrangement of the several parts which will be more fully described in the subjoined description and pointed out in the appended claims.

In the drawings:

Fig. 1 is an elevation of the improved drill jar comprising dual jar units of similar construction, the jar members or units being shown open.

Fig. 2 is a view similar to Fig. 1, showing the jar members or units in closed position.

Fig. 3 is a similar view with parts shown in section, or one of the jar members or units cut through to illustrate the manner of assembling the dual units.

Fig. 4 is a transverse section on the line 4—4, Fig. 2.

Fig. 5 is a transverse section on the line 5—5, Fig. 1.

The improved jar comprises two link members A and B, which are precisely duplicate in construction except in the attaching details which will be presently explained. The upper extremity of the member A is in the form of a body 5 preferably cylindrical in cross section and having a screw-threaded socket 6 for attachment of a coupling device at the lower end of its suspending cable, not shown. The lower extremity of the member B is likewise in the form of a body 7 mainly cylindrical in cross section and having a lower screw-threaded nipple 8 for attachment to a drilling tool. The bodies 5 and 7 are respectively formed with flat or squared faces 9 and 10, to provide seats for a wrench or spanner to hold the members stationary during attachment or detachment of the suspending cable and drilling tool. Each body 5 and 7 has a pair of reins 11 and 12 extending therefrom and transversely slotted as at 13, the terminals of the slots being converged at one extremity of each as at 14, the said reins having the opposite portions thereof along the side walls of the slots cut away to form longitudinal seats 15, the said seats extending from transversely straight shoulders 16 to the converged extremities 14 of the slots 13. The opposite cut-away portions forming the seats 15 adjacent the converged extremities 14 of the slots 13 incline outwardly as at 17, this seat and outwardly inclined terminal construction being duplicated on opposite sides of each rein, and also each rein is formed on opposite sides with the transversely straight abutting shoulders 16. The slots 13 of the two rein members 11 and 12 are reversely positioned, or the converged extremity 14 of the member 11 is located adjacent the body 5 and the similar converged extremity of the slot 13 of the member 12 is located adjacent the body 7 of said latter rein member. The slots 13 of the two rein members are formed for the purpose of permitting sliding assemblage of the two rein members, and each slot is centrally divided in a longitudinal direction by a web or tongue 18 which is located within the head 19, the latter having opposite flanges 20 projecting outwardly beyond the opposite sides of the tongue 18. The seats 15 formed by cutting

away the opposite portions of each rein member are directly in rear of the heads 19, or, as hereinbefore indicated, terminate coincidently with the transversely straight shoulders 16, and the inner ends of the tongues 18 form the terminal walls for the slots 13 at the extremities of the latter opposite the converged extremities 14 thereof. The inner opposing sides of the flanges 20 of the heads are gradually converged towards the outer terminals of the said heads and are formed as convex bevels 21, which are of the same curved contour or arc curvature as the outwardly beveled extremities 17 of the said seats 15 formed by cutting away the opposite portions of the rein members. The outer ends 22 of the tongues 18 terminate slightly inside of the outer terminals of the heads 19, the outer surfaces of the heads and of the shanks 23 formed between the respective bodies 5 and 7 having a general convex contour, and, as hereinbefore indicated, the said bodies are also of the same contour with the exception of the square or flat faces 9 and 10. It will therefore be seen that the assembled reins conjointly provide a cylindrical jar which will be of a uniform diameter throughout its length in accordance with the diameter of the opening in which the improved jar is adapted to operate. The inner terminals of the heads 19 which are formed with the transversely straight shoulders 16 have a positive square abutting operation and the engagement of the outer ends of the same heads with the outwardly concaved curved terminals of the seats 15 insure an abutting check when the heads 19 shift longitudinally, but the abutting engagement at this portion of the improved jar will be easy with respect to the two rein members, in view of the curvature of the extremities 17 of the said seats and the corresponding curvature of the extremities 21 of the flanges 20 of the said heads. The outer ends 24 of the said heads are regularly curved or continue in a semi-elliptical form from one side to the other thereof, or are of exactly the same contour as the outwardly curved terminals 17 of the seats 15, so that there will be a snug fitting of these cooperating parts. The movement of the outer curved ends with the flanges 20 having their front extremities formed with convex bevels 21 as hereinbefore explained, when the said heads are forced apart or the shoulders 16 thereof separated as shown by Fig. 2, will operate to take up a portion of the shock or jar but with an easy action, as also hereinbefore specified, and thereby eliminate a too sudden check or abrupt contact and prevent wear on the heads 19 and tongues 18. Moreover, by extending the tongues 18 only to and coincidently with the outward limit of the heads 19, the said tongues are strengthened and are less liable to become

fractured or broken, and to facilitate the easy movement of the heads with relation to the seats and the outwardly curved extremities 17 of said seats, the tongues have their outer terminals reduced, as at 25, by 70
versely curved bevels 26.

From the foregoing the operation of the present improved jar will be obvious. After its application at one end to a cable and equipment at the other end with a drill 75 tool, as is customary, it is reciprocated through the action of well known mechanism in well boring operations, and when the jar descends the two links or rein members come together the moment the drill tool 80 strikes an obstruction, and upon elevation of the jar through the cable for further impact of the drill tool with respect to the material being bored, the links or rein members separate. When the two links or rein 85 members close at the time of impact of the drill tool with the material bored, the transversely straight shoulders 16 come together and uniformly distribute the impact stress relatively to the jar at opposite sides of the 90 latter, and when the links or rein members open, the outer rounded ends of the heads 19 gradually move into the outwardly curved inclined extremities of the seats 15 with an easy action in view of the structure 95 of these cooperating parts as hereinbefore specified. It will be understood that in assembling the links or rein members they are primarily separate and subsequent to assemblage as shown in the drawings the 100 members are rendered continuous and inseparably connected by welding the joints along the lines $a-b$. It is proposed to form the links or rein members of suitable hard material or metal as to withstand wear and 105 to so proportion the slots 13 and tongues 18 that there will be an easy sliding movement with minimized lateral play, and the tapered or reduced extremities 25 of the tongues will enter the reduced or tapered extremities 14 of the slots without sticking, and by this means an alternate opening and closing movement of the links or rein members will be sensitively effected.

The welding joint along the lines $a-b$ 115 is of V-shaped form as shown by Figs. 1 and 2 with the angle of the weld outermost towards the screw-threaded nipple 8 forming the terminal of the body 7 of the member B. This form of welded joint is materially advantageous in its location and contour. It will be noted that this welded joint is located outwardly beyond the extreme limit of the outwardly curved inclines 17 adjacent the converged extremities 120 14 of the slots 13, and the terminals of the flanges 20 of the heads 19 serve to protect the welded joint, due to the fact that they act as a bracing means on both sides of the weld seam, and by this means any expansion 125 130

caused by the tongues in the jars now in use is prevented.

What is claimed as new is:

1. A jar of the class specified comprising two duplicate link members each having a body with inwardly projecting reins with centrally disposed longitudinal slots extending partway of the length thereof and terminating in inner transversely straight shoulders from which seats on opposite sides of the slots extend towards the body and terminate in outward curved concave extremities, the reins having their inner ends shaped as heads with rounded free ends and having tongues centrally disposed therein and of less width than the heads to form flanges which are slidable in the said seats, the tongues terminating inwardly a distance from the free rounded ends of the heads, the heads being wider than the remaining portions of the reins.
2. A drill jar of the class specified comprising duplicate link members having slots extending longitudinally partway of the length thereof and terminal heads with transversely extending tongues, the link members having their inner portions formed as reins terminating in the said heads and engaging seats along the slots, the seats having at one end terminal outwardly inclined concave extremities and the heads being movable in the said seats flush with the adjacent parts of the respective link members, the heads and tongues of the respective link members also being disposed at right angles to each other and the heads

on opposite sides of the tongues having flanges terminating in outward reduced curved bevels adjacent the outer ends of the tongues to fit in and have an easy checking action to the closing movement of the link members by engagement with the outwardly curved extremities of the seats, the heads having opposing transversely straight shoulders which abut when the link members are pulled into open position or separated for a portion of their lengths.

3. A drill jar of the class specified comprising duplicate link members having inner slidably associated elements consisting of heads with transversely extending tongues and longitudinal slots engaged by the tongues, the tongues terminating within the ends of the heads, the tongues and slots having reduced extremities for interfitting sliding action, the parts of the link members adjacent the extremities of the slots opposite the reduced extremities of the latter having straight transverse shoulders which have abutting contact when the link members are pulled longitudinally and opened, the free ends of the heads on the opposite sides of the tongues being reduced and formed with curved bevels and the members adjacent the reduced extremities of the slots having outwardly curved seat portions for engagement by the free extremities of the heads.

In testimony whereof I have hereunto set my hand.

EDWARD J. DUNIGAN.
